(57) CLAIM

The ornamental design for a toiletries holder, as shown and described.

DESCRIPTION

FIG. 1 is a front view of a toiletries holder showing my new design;

FIG. 2 is a rear view of the toiletries holder;

FIG. 3 is a right side view of the toiletries holder;

FIG. 4 is a left side view of the toiletries holder;

FIG. 5 is a top view of the toiletries holder;

FIG. 6 is a bottom view of the toiletries holder; and,

FIG. 7 is a top front perspective view of the toiletries holder. The broken lines are illustrative of environmental structure forming no part of the claimed design.
